(57) **CLAIM**

The ornamental design for RF connector as shown and described.

DESCRIPTION

1.1: Perspective

1.2: Front

1.3: Back

1.4: Left

1.5: Right

1.6: Top

1.7: Bottom

1.8: Bottom respective view

The present design No. 1 relates to an RF connector which would be mounted on a printed circuit board and configured to transmit a radio-frequency (RF) signal; **1.1** is a view illustrating an overall shape thereof; **1.2** is a view illustrating a front side thereof; **1.3** is a view illustrating a rear side thereof; **1.4** is a view illustrating a left side thereof; **1.5** is a view illustrating a right side thereof; **1.6** is a view illustrating a top side thereof; **1.7** is a view illustrating a bottom thereof; **1.8** is a bottom perspective view illustrating an overall shape thereof; in the present design, solid lines are used to represent features that form a part of the design, and broken lines are used to represent features that do not form a part of the design; and no claim is made by virtue of this registration in respect of broken lines appearing in the article.
